US00D677313S

(12) **United States Design Patent**
Markovitz et al.

(10) **Patent No.:** **US D677,313 S**
(45) **Date of Patent:** **** Mar. 5, 2013**

(54) **EYEGLASSES**(75) Inventors: **Aaron Markovitz**, New York, NY (US);
Artiss Akarra, Johnston, RI (US)(73) Assignee: **Cross Optical Group, Inc.**, Daytona Beach, FL (US)(**) Term: **14 Years**(21) Appl. No.: **29/405,471**(22) Filed: **Nov. 2, 2011**(51) **LOC (9) Cl.** **16-06**(52) **U.S. Cl.** **D16/315**; D16/335(58) **Field of Classification Search** D16/101,

Primary Examiner — Raphael Barkai(74) *Attorney, Agent, or Firm* — Malloy & Malloy, P.L.(57) **CLAIM**

The ornamental design for eyeglasses, as shown and described.

DESCRIPTION

FIG. 1 is a front plan view illustrating our design for eyeglasses;

FIG. 2 is a top view thereof;

FIG. 3 is a left side view thereof; the right side being a mirror image thereof;

FIG. 4 is a front perspective view thereof;

FIG. 5 is a rear view thereof; and,

FIG. 6 is a bottom view thereof.
